POURING DEVICE

Raymond J. Moran, Rochester, N. Y., and John L. Nilson, Chicago, Ill.

Application May 26, 1941, Serial No. 395,134

3 Claims. (Cl. 215—79)

Our invention relates to a device adapted to be attached to bottles or the like to aid in pouring liquids therefrom, and to substantially prevent refilling of the bottles.

Among the objects of our invention is to provide a device adapted to be readily attached to a container such as a bottle for pouring liquids therefrom. Our device is also constructed to substantially prevent the refilling of the containers, and such other objects, advantages and capabilities as will later more fully appear and which are inherently possessed by our invention.

While we have shown in the accompanying drawing a preferred form of our invention, yet we desire it understood that the same is susceptible of modification and change without departing from the spirit of our invention.

Referring to the drawing, Fig. 1 is a side elevational view of our pouring device in position in a bottle; Fig. 2 is a top plan view of our pouring device; Fig. 3 is a detailed rear elevational view; Fig. 4 is an enlarged detailed sectional view on line 4—4 of Fig. 3; Fig. 5 is a bracketed side elevational view of the cap removed from the body member; Fig. 6 is a bottom view of our pouring device; Fig. 7 is a detailed sectional view on line 7—7 of Fig. 4; Fig. 8 is a detailed sectional view on line 8—8 of Fig. 4.

Referring to the embodiment selected to illustrate our invention, it comprises a body portion 10 having a lower hollow shank 11. A hollow liquid flow tube 12 extends above the body member 10 and communicates with a passage 13 extending downwardly within body member 10 so only a part of the lower end of passage 13 is in register with the upper end of hollow shank 11. In other words the passage 13 is offset with relation to the hollow shank 11.

A hollow air flow tube 14 extends above the body member 10 and communicates with a passage 15 extending downwardly within body member 10. Said passage 15 is offset so as to have partial communication with hollow shank 11.

A vent tube 16 extends upwardly through shank 11 and has its upper end seated within a recess 17 formed in the body member 10 so as to provide air passing through said tube 16 from the air flow tube 14 to the container.

A cap 18 slips over seat 19 formed on top of body member 10 and is attached to body member 10 by friction grip or any other suitable means.

The cap 18 has a chamber 20 covering the liquid flow tube 12, and another chamber 21 covering the air flow tube 14. A spout 22 communicating at its inner end with the chamber 20 and

5 has an open outer end 23. The spout 22 is opposite the tubes 12 and 14. The chamber 20 is of such a size and diameter as to accommodate liquid to reach the spout 22 before the liquid reaches the level of the openings 24.

10 Openings 24 are cut through adjacent walls of chambers 20 and 21 and also lead to the atmosphere. Another opening 25 is cut through an opposite wall of chamber 21. Openings 24 and 25 are lower in position than the upper ends or tops of liquid flow tube 12 and air flow tube 14. The outer end 23 of spout 22 is lower than the upper ends of liquid flow tube 12 and air flow tube 14.

15 A lug 26 is provided adjacent the lower end of the spout 22 so as to contact the edge of a glass or container to aid in the pouring operation.

20 In use our device is readily adapted for attachment by means of a cork 30 surrounding shank 11. In pouring, air passes in through air flow tube 14 down into vent tube 16 to displace liquid passing through liquid flow tube 12 and out spout 22.

25 It has long been a problem to prevent the refilling of bottles, particularly bottles from which expensive liquids are dispensed. With our device if refilling liquid is poured or forced down into the mouth 23 of spout 22 the liquid strikes against liquid flow tube 12 and the walls of chamber 20 and cannot rise above the higher level of the 30 top of the tube 12. The liquid then passes out openings 24 into chamber 21 and out opening 25. Openings 24 also lead to the atmosphere, so that some liquid passes out at these points. Other liquid passes out through openings 27 and 35 28 cut out of body member 10.

30 Liquid attempted to be introduced into opening 25 will pass out openings 24, spout 22 or other openings. Substantially no liquid enters the high tops of tubes 12 and 14.

40 When alcoholic liquor is in the container when used with our device, alcoholic fumes from the liquor in the container pass upwardly to the upper portions of chambers 20 and 21 and tend to remain there because the air below is heavier.

45 This prevents evaporation or loss of alcohol of the liquor in the container.

45 A seal of any desired kind may be applied to our device after it has been attached to a container, to expose premature removal of the 50 device.

Having thus described our invention, we claim:

1. A pouring device comprising a body member having a lower hollow shank adapted to be attached to a container, an air supply tube with its upper end extending above said body mem-

ber, said body member having an air supply passage communicating with the lower end of said air supply tube, said body member also having a liquid flow passage, a liquid flow tube with its upper end extending above said body member and having at its lower end offset communication with said liquid flow passage, a cap attached to said body member, said cap extending slightly above and across the upper ends of said tubes, a spout communicating with the interior of said cap at a point lower than the upper ends of said tubes, said cap having openings extending into its interior, said openings positioned below the upper ends of said tubes, so that refilling liquid passed through said spout or said openings will pour out of said openings before reaching the upper ends of said tubes.

2. A pouring device comprising a body member having a lower hollow shank adapted to be attached to a container, an air supply tube and a liquid flow tube extending above said body member, said body member having passage ways therein communicating with said tubes, a cap attached to said body member, said cap extending slightly above and across the upper ends of said tubes, said cap having a partition separating the portion protecting the air supply tube from that protecting the liquid flow tube, a spout communicating with the interior of said cap at a point lower than the upper ends of said tubes, 30

said cap having openings extending into its interior, said openings positioned below the upper ends of said tubes so that refilling liquid passed through said spout or said openings will pour out of said openings before reaching the upper ends of said tubes.

3. A pouring device comprising a body member having a lower hollow shank adapted to be attached to a container, an air supply tube and a liquid flow tube extending above said body member, said body member having passage ways therein communicating with said tubes, a cap attached to said body member, said cap extending slightly above and across the upper ends of said tubes, said cap having a partition separating the portion protecting the air supply tube from that protecting the liquid flow tube, a spout communicating with the interior of said cap at a point lower than the upper ends of said tubes, 10 said cap having openings in its walls and also in said partition, said openings extending into the interior of the cap, and positioned below the upper ends of said tubes, said body member also having openings so that refilling liquid passed through said spout or said openings will pour out of said openings before reaching the upper ends of said tubes.
